UNITED STATES PATENT OFFICE

161,881

INVERTIBLE OIL BURNER UNIT

Andrew N. Sorensen, Chicago, Ill.

Application May 8, 1950, Serial No. 9,806

Term of patent 14 years

(Cl. D81—2)

To all whom it may concern:

Be it known that I, Andrew N. Sorensen, a citizen of the United States, residing in Chicago, in the county of Cook and State of Illinois, have invented a new, original, and ornamental Design for an Invertible Oil Burner Unit, of which the following is a specification, reference being had to the accompanying drawings forming part thereof, in which:

Fig. 1 is a perspective view taken from the front and to one side of an invertible oil burner embodying my new design, showing the unit mounted in one upright position;

Fig. 2 is a perspective view similar to Fig. 1, showing the unit mounted in a position inverted with respect to that shown in Fig. 1;

Fig. 3 is a perspective view taken from the rear and other side of the oil burner unit mounted in the position shown in Fig. 2;

Fig. 4 is a rear elevational view of the unit mounted in the position shown in Fig. 1; and

Fig. 5 is a top plan view of the unit mounted in the position shown in Figs. 1 and 4.

I claim:

The ornamental design for an invertible oil burner unit, substantially as shown.

ANDREW N. SORENSEN.
